CLAIM

I claim the ornamental design for a clip for apparel or household decor, as shown and described.

DESCRIPTION

FIG. 1 is a top plan view of the clip with a designation for any type of optional design.

FIG. 2 is a bottom plan view of the clip.

FIG. 3 is a front plan view of the clip; and,

FIG. 4 is a side plan view of the clip.

1 Claim, 4 Drawing Sheets
